UNITED STATES PATENT OFFICE

2,206,317

LOOSE LEAF BINDER

Herbert H. Behn, Chicago, Ill.

Application December 9, 1938, Serial No. 244,778

3 Claims. (Cl. 129—24)

The invention relates to loose leaf binders where rings made in sections are separable to permit insertion or removal of sheets of paper.

While numerous constructions of loose leaf binders are on the market, yet they prevent the easy manipulation of a large number of sheets, particularly by reason of the fact that the rings are arranged between the backs of the book and the separation of the ring sections is only possible to a limited extent and because the rings are normally rigidly secured to the backs.

It is, therefore, an object of the invention to provide a loose leaf binder which affords a maximum of freedom of movement for the rings, enabling the facile manipulation of a large number of loose leaves or sheets.

A further object constitutes the provision of a holder for the rings, which holder is constructed and arranged to avoid interference with the manipulation of the sheets.

A still further object constitutes the provision of sectionalized rings which are pivotally secured to the holders, allowing tilting of the ring sections at all times.

Another object is the provision of means for maintaining the ring sections under tension, so that the rings do not lose their efficacy even after protracted use, and may be collapsed without breaking.

Other and equally important objects will become apparent from a perusal of the invention comprising the means described in the following specification, particularly pointed out in the claims forming a part thereof, and illustrated in the accompanying drawing, in which:

Fig. 1 is a perspective view of a book, in which my invention may be incorporated.

Fig. 2 is an enlarged view of the upper part of the book.

Fig. 3 is a section on the line 3—3 of Fig. 2.

Fig. 4 is a side view of the ring, and

Fig. 5 is a section through the ring and associated parts.

Referring to the several views in the drawing, the invention is illustrated in connection with an order book, but may be applied wherever loose leaf binders are required.

The book comprises a back 10 which, at the lower end, is turned up to form a panel 11, and thence is connected by a flexible portion 12 to a cover 13.

To the back 10, at the upper end thereof, is secured a plate 14 by a plurality of rivets 15, but any other means for securing the plate may be chosen, if so desired.

The plate 14 projects beyond the upper edge of the back and is curled to provide a sleeve 16.

The rings 17 are made up in halves 18 and 19 which, at one end, are offset as at 20 to overlap, and are provided with an aperture for the passage of a rod 21 provided at one end with a head 22 and, at the other end, with screw threads to receive nuts 23.

A washer 24 is placed on each side of the ring and is held in engagement therewith by a spring 10 25 bearing on the nuts 23 and a spring 26, bearing against the head 22.

The rod 21 is arranged inside the sleeve 16, there being a slot 27 in the sleeve for each ring, to permit free movement thereof. The ends of 15 the ring sections are provided with teeth 28 which interfit when the ring sections are closed.

It is evident that the rings 17 are rotatably held in the sleeve and may be freely swung around the rods 21, so that they are particularly 20 fitted for accommodating a large number of sheets 29, which may be conveniently swung from one side to the other giving practically a range of 360°, inasmuch as the rings may be swung around and the sleeve 16 is comparatively thin. 25

Attention is called to the fact that the sleeve 16 is arranged beyond the upper edge of the back so that no interference is possible in manipulating the sheets to transfer them from one side of the back to the other.

By reason of the provision of springs for holding the ring sections in frictional engagement, the rings may be forced together beyond the closing position without breaking them.

While the drawing discloses a preferred embodiment of the invention, various changes and alterations may be made without departing from the spirit of the invention.

I, therefore, do not limit myself to details of construction, as shown, but include all modifications and variations constituting departures within the scope of the invention, as defined in the appended claims.

I claim:

1. In a device of the character described, a plate curled at one edge to provide a sleeve, a plurality of sectionalized rings arranged in slots provided in said sleeve, means for maintaining the sections of each ring in frictional engagement, and means for rotatably securing said rings to said sleeve, said first and second named means being housed in said sleeve.

2. In combination with the cover of a book, a plate secured thereto and projecting therebeyond, the protruding plate portion being rolled into a

- sleeve and provided with slots, sectionalized rings in said slots and rotatably secured to said sleeve, and means in said sleeve for maintaining the sections of each ring in frictional engagement.
5. 3. In combination with the cover of a book, a plate secured thereto and projecting therebeyond, the protruding plate portion being rolled into a

sleeve and provided with slots, sectionalized rings in said slots, means for rotatably securing said rings to said sleeve, and means for maintaining the sections of each ring in frictional engagement, said first and second named means being 5 housed in said sleeve.

HERBERT H. BEHN.
